UNITED STATES PATENT OFFICE

143,670

DESIGN FOR A COMBINED KNIFE AND GRIPPING TOOL

Irwin H. Palmer and Ray F. Williamson,
Aberdeen, S. Dak.

Application April 21, 1945, Serial No. 119,125

Term of patent 14 years

(Cl. D22—3)

To all whom it may concern:

Be it known that we, Irwin H. Palmer and Ray F. Williamson, citizens of the United States, residing at Aberdeen, in the county of Brown and State of South Dakota, have invented a new, original, and ornamental Design for Combined Knife and Gripping Tool, of which the following is a specification, reference being had to the accompanying drawing forming part thereof.

In the drawing:

Fig. 1 is a perspective view of the combined knife and gripping tool, showing our new design.

Fig. 2 is a similar view looking from the opposite side thereof.

We claim:

The ornamental design for a combined knife and gripping tool, as shown.

IRWIN H. PALMER.
RAY F. WILLIAMSON.
